UNITED STATES PATENT OFFICE.

EUGENE A. HAWKINS, OF NORTH ATTLEBORO, MASSACHUSETTS.

DESIGN FOR A MESH-BAG.

46,731.

Specification for Design.

Patented Dec. 8, 1914.

Application filed September 22, 1914. Serial No. 863,013. Term of patent 3½ years.

To all whom it may concern:

Be it known that I, EUGENE A. HAWKINS, a citizen of the United States, residing at North Attleboro, in the county of Bristol and State of Massachusetts, have invented a certain new, original, and ornamental Design for a Mesh-Bag, of which the following is a specification.

In the accompanying drawings which form a part of this specification, Figure 1 is

a side elevation of a mesh bag embodying my design, and Fig. 2, an end elevation of the same.

What I claim is,—

The ornamental design for a mesh bag, as shown.

EUGENE A. HAWKINS.

Witnesses:

CHARLES L. JENCKES,
HORATIO E. BELLOWES.
